UNITED STATES PATENT OFFICE.

WILLIAM A. SUDDITH AND J. F. SUDDITH, OF CHARLESTOWN, VIRGINIA.

WASHING-MACHINE.

Specification of Letters Patent No. 25,058, dated August 9, 1859.

To all whom it may concern:

Be it known that we, W. A. SUDDITH and JNO. F. SUDDITH, of Charlestown, in the county of Jefferson, in the State of Virginia, have invented a new and useful Improvement in Washing-Machines; and we do hereby declare that the following is a full, clear, and exact description of the construction of the same, reference being had to the annexed drawing, making a part of this specification, in which—

Figure 1, is a perspective view, &c.

The nature of our invention consists in washing clothes viz: A semicylinder with a diagonal corner and spiral spring attached to the hinge part of cylinder as shown in

drawings at Fig. 4. Fig. 6 is a rack moved by screws at Fig. 5, to admit more or less clothes. Fig. 3 is a diagonal block at one end (two inches thick), upon which the cylinder is formed. Fig. 2 is a shaft upon which the cylinder turns. Fig. 7 is the hinged part of cylinder. Fig. 8 is the spiral spring with a rod through spiral spring. 25
20

We claim—

The hinged part of cylinder as set forth in drawings at Fig. 7.

W. A. SUDDITH.

JOHN F. SUDDITH.
